Attorney

UNITED STATES PATENT OFFICE.

LOUIS L. ANSART, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed April 26, 1922. Serial No. 556,626.

To all whom it may concern:

Be it known that I, LOUIS L. ANSART, a citizen of the United States, residing in borough of the Bronx, in the county of the

5 Bronx, city and State of New York, have invented certain new and useful Improvements in Typewriting Machines, of which the following is a specification.

This invention relates to means for centering headings or the like on work-sheets in typewriting machines, and is illustrated in connection with the device shown in the 10 patent to H. Bates and C. E. Smith, No. 1,146,393, of July 13, 1915. It is also applicable to other devices, as, for example, that 15 shown in the application of B. F. Barker, Serial No. 543,635, filed March 14, 1922.

In carrying out the present invention, provision is made of means whereby the setting 20 of right and left margin-stops at any selected positions automatically effects the setting of a centering pointer midway between the margin-stops. The mechanism by 25 which the margin-stops control the position of the centering stop may be substantially the same as in said patent to H. Bates and C. E. Smith. Provision may also be made of a half-letter-space scale, similar to that of the Barker application but positioned so 30 that its graduations are numbered from "0," coinciding with the central pointer on the carriage, to the left.

After setting the margin-gages in the desired positions and determining the number 35 of letter-spaces in the heading to be centered, the only step necessary, preparatory to typing the heading in centered position with reference to the margin-gages, is to shift the carriage to bring the graduation, 40 on the half-letter-space scale and having the same number as the letter-spaces in the heading, into alignment with the centering pointer.

Other features and advantages will hereinafter appear.

In the accompanying drawings,

Figure 1 is a front view, showing my invention applied to so much of an Underwood standard typewriter as is necessary 50 for the purpose of illustration, the margin-gages being set in the selected positions.

Figure 2 is a fragmentary view similar to Figure 1, but showing the carriage positioned to begin typing a heading in centered 55 position between the margin-stops.

Figure 3 is a view similar to Figure 2, but showing the margin-gages set in positions different from those occupied in Figure 2.

Provision is made of a left margin-stop 60 11 and a right margin-stop 12, both slidably mounted on a rod or bar 13 supported at the left and right, respectively, by the ends 14 and 15 of the typewriter-frame. The left margin-stop 11 is provided with a pivoted 65 finger-piece 16 having an arm 17 connected with the forward end of a pin 18 guided in lugs 19 and pressed rearwardly by a spring 20. The pin 18 normally engages the rod 13, so as to hold the margin-stop 11 against 70 movement transversely of the machine in a manner which is more fully described in said patent to H. Bates and C. E. Smith. Upon pressing the finger-piece 16 toward a fixed finger-piece 21 on the margin-stop 11, 75 the pin 18 will be withdrawn from its effective position and the margin-stop 11 may be moved to any desired position along the rod 13, the desired position being determined by the position of a pointer 22 on the 80 margin-stop 11 with reference to the usual letter-space scale 23 mounted on the cross-bar 24 at the front of the machine. The right margin-stop 12 is also provided with a fixed finger-piece 25 and a pivoted finger-piece 26 having an arm 27 connected with a pin 28 guided in lugs 29 and pressed to the rear by a spring 30 to co-operate with the bar 13 to hold the margin-stop 12 in adjusted position. The right margin-stop 12 90 is also provided with a pointer 31 to co-operate with the letter-space scale 23 in positioning the margin-stop.

A centering pointer 32 is slidably mounted on the rod 13 and extends to the upper 95 edge of the letter-space scale 23 for a purpose to be described more fully hereinafter. In order to maintain the centering pointer 32 midway between the margin-stops 11 and 12, irrespective of the positions of the latter, 100 a pinion 33 mounted on the centering pointer 32 meshes with a rack 34 fixedly connected with the left margin-stop 11, and a rack 35 fixedly connected with the right margin-stop 12, the centering pointer being so 105 constructed as to hold the racks 34 and 35 in mesh with the pinion 33. The means just described for automatically maintaining the centering pointer 32 midway between the margin-stops 11 and 12 is substantially the 110

same as that disclosed in said patent to H. Bates and C. E. Smith.

As herein disclosed, the carriage, which may be indicated in general by the reference numeral 36, is provided with a front bar 37 adjacent to the letter-space scale 23, and with the usual central pointer 38 to co-operate with the letter-space scale 23. In order to facilitate the positioning of the carriage preparatory to typing a heading, or the like, in centered position between the margin-stops 11 and 12, provisions is made of a half-letter-space scale 39 having its "0" graduation in coincidence with the central pointer 38 and the other graduations numbered to the left therefrom, the lower edge of the half-letter-space scale 39 lying along the upper edge of the letter-space scale 23 as the carriage travels transversely of the machine. The pointers 22 and 31 of the left and right margin-stops 11 and 12, respectively, extend only partway across the letter-space scale 23, but, as hereinbefore stated, the centering pointer 32 is extended to the upper edge of the letter-space scale 23 so as to be close to the lower edge of the half-letter-space scale 39 which co-operates therewith in determining the position of the carriage preparatory to typing the heading in centered position.

When a heading of a given number of letter-spaces is to be centered with reference to the position of the margin-stops, half of the heading is to be written on the working sheet at the left of the central pointer 38, and the other half at the right. It is therefore necessary to bring the carriage to a preliminary position in which the pointer 38 is positioned at the right of the centering pointer 32 a number of letter-spaces, half that in the heading. This distance is the same as that occupied by the number of half-letter-spaces corresponding to the number of whole letter-spaces in the heading, and the preliminary position of the carriage may, therefore, be obtained by bringing the half-letter-space graduation, corresponding in number to the number of letter-spaces in the heading, opposite the centering pointer 32.

As shown in Figures 1 and 2, the margin-stops 11 and 12 are positioned for the letter-space positions 68 and 4, respectively, on the scale 23, and the centering pointer 32 is positioned over the graduation 36 of the letter-space scale, the carriage being shown in Figure 1 in the position in which it happened to be before shifting to a position for typing the heading in centered position. As shown in Figure 3, the carriage 36 has been shifted to bring the graduation 20 on the half-letter-space scale 39 into alignment with the centering pointer 32, thus positioning the carriage for centering a heading of twenty letter-spaces between the margin-stops.

Figure 3 shows the margin-stops placed in different positions from those occupied in Figure 2, and the carriage again positioned for centering the heading of twenty letter-spaces thereon.

Variations may be resorted to within the scope of the invention, and portions of the improvements may be used without others.

Having thus described my invention, I claim:

1. In a typewriting machine, in combination, a carriage having a letter-feeding movement, margin-stops adjustable to different positions to determine the limits of movement of said carriage, and heading-centering means, comprising a half-letter-space scale on the carriage and a pointer to co-operate therewith, whereby the carriage may be brought to the proper preliminary position for typing the heading in centered position, with reference to the margin-stops, by placing in alignment the pointer and a graduation of the half-letter-space scale corresponding to the number of letter-spaces in the heading.

2. In a typewriting machine, in combination, a carriage having a letter-feeding movement, margin-stops adjustable to different positions to determine the limits of movement of said carriage, and heading-centering means, comprising a scale on the carriage and a pointer to co-operate therewith, whereby the carriage may be brought to the proper preliminary position for typing the heading in centered position, with reference to the margin-stops, by bringing into coincidence the pointer and a graduation of the scale corresponding to the number of letter-spaces in the heading.

3. In a typewriting machine, in combination, a carriage having a letter-feeding movement, margin-stops adjustable to different positions to determine the limits of movement of said carriage, and means for centering a heading between said margin-stops, comprising two elements, a half-letter-space scale on the carriage and a pointer controlled by the margin-stops, whereby the carriage may be positioned for typing the heading by placing in alignment the pointer and the graduation of the half-letter-space scale corresponding to the number of letter-spaces in the heading.

4. In a typewriting machine, in combination, a carriage having a letter-feeding movement, margin-stops adjustable to different positions to determine the limits of movement of said carriage, and means for centering a heading between said margin-stops, comprising two elements, a scale and a pointer, one of which is controlled by the carriage and the other by the margin-stops, whereby the carriage may be positioned for typing the heading by placing in alignment the pointer and the graduation of the scale

corresponding to the number of letter-spaces in the heading.

5. In a typewriting machine, in combination, a carriage having a letter-feeding movement, margin-stops adjustable to different positions to determine the limits of movement of said carriage, a centering pointer connected with said margin-stops to be maintained midway therebetween, irrespective of the positions of the latter, and a half-letter-space scale extending from the middle of the carriage in the letter-feeding direction, whereby the carriage may be positioned for centering a heading of a predetermined number of letter-spaces by bringing the graduation of the half-letter-space scale, corresponding to said predetermined number, into alignment with said centering pointer.
- 10 6. In a typewriting machine, in combination, a carriage, a fixed letter-space scale extending transversely of the machine, margin-stops settable at letter-space distances along said letter-space scale, a centering pointer movable along said letter-space scale, means controlled by the margin-stops for automatically centering said centering pointer with reference thereto, and a half-letter-space scale on said carriage extending to the left from the middle of the carriage, whereby the carriage may be positioned for typing in centered position a heading of a predetermined number of letter-spaces by bringing the graduation on the half-letter-space scale, corresponding to said predetermined number, into alignment with said centering pointer.
- 15 7. In a typewriting machine, in combination, a carriage, a central pointer thereon, a fixed letter-space scale to co-operate with said central pointer to indicate the letter-space position of the carriage at any time, margin-stops settable at line-space distances along said letter-space scale, a centering pointer movable along said letter-space scale,

means controlled by the margin-stops for automatically centering said centering pointer with reference thereto, and a half-letter-space scale on said carriage having its "0" graduation in coincidence with said central pointer and its graduations numbered from said "0" graduation in the direction of carriage travel, whereby the carriage may be positioned for typing a heading in centered position by bringing into coincidence the centering pointer and the graduation of the half-letter-space scale corresponding to the number of letter-spaces in said heading.

55 8. In a typewriting machine, in combination, a fixed letter-space scale extending transversely of the machine, a centering pointer settable along said scale to indicate the center of a heading to be typed on a work-sheet, and a half-letter-space scale on the carriage to cooperate with said pointer, said scale having its "0" graduation at the middle of the carriage and the other graduations numbered to the left from said "0" graduation, whereby, upon bringing into coincidence the centering pointer and the graduation on the half-letter-space scale corresponding in number to the number of letter-spaces in the heading, the carriage will be properly positioned for typing the heading in centered position with reference to said centering pointer.

60 9. In a typewriting machine, in combination, a letter-feeding carriage and a heading-centering scale mounted on the carriage with its "0" point at the middle of the carriage, said scale extending to the left and so numbered that the number indication at any point is twice the number of letter-spaces in the interval between the "0" and said point.
